ELECTRIC RAZOR HAIR CUTTING ATTACHMENT

Albert S. Haislip, Fredericksburg, Va.

Application April 12, 1954, Serial No. 422,375

14 Claims. (Cl. 30—34)

The present invention relates to certain new and useful improvements in an attachment for so-called electric razors, or dry shavers, as they are sometimes called, that is, an attachment which is expressly and therefore properly designed and constructed to enable one to cut his own hair.

It will be clear, having read the preceding general statement of the invention, that the art to which the invention relates teaches that it is possible and practicable to provide an appropriately constructed device or attachment which enables users to frequently trim and cut the hair at the temples and above the nape of the neck, thus keeping these marginal areas neat and presentable.

An object of the instant invention is, therefore, to structurally, functionally and otherwise improve upon similarly constructed and performing prior art hair cutting attachments and, in doing so, to provide a novel and distinct construction in which manufacturers and users will find their respective requirements and needs acceptably met.

Although it is within the purview of the inventive concept to provide an attachment which lends itself to cooperative use with various makes of electric razors, the attachment herein disclosed is especially, but not necessarily, adapted to be used in conjunction with a Remington dry shaver. To this end, it is therefore another object of the invention to provide a hair cutting attachment which is characterized, in part, by a specially designed holder which takes the form of a tray-like receiver into which a half-portion of the body of the electric razor is placed, the receiver conforming to the contour of the coacting portion of the body and thus effecting intimate conformation and making it possible to hold the razor and receiver as a unit and to move the razor up and down in vertical paths with the utmost of ease and for adequate guidance in attaining end results with precision and reliability.

Briefly summarized, and regardless of the type of electric razor mentioned, the invention has to do with a hair cutting attachment comprising an adapter which conformably fits itself to and is handily retained on the body of the razor, means including at least one toothed comb which assumes operative relation to the existing or stock cutter means of the usual cutter head of the razor, and additional means for retaining said first named means on said adapter.

Then, too, novelty is predicated on the construction described wherein said first named means embodies two combs, one which travels with an "up" stroke in a vertical path of movement to collect and cut the hair-ends, and the other which serves to straighten and comb the hairs back to desired place during the "down" stroke.

More explicitly, the attachment is characterized by a substantially rectangular plate having a lengthwise central bend defining complementary flat half-portions, the respective outer longitudinal edges thereof being toothed and providing progressively and selectively usable combs,

2

said half-portions being in slight divergent relation in respect to said bend, one of said half-portions having key-hole slots therein, and the combination therewith of a tray-like razor receiver and holder, the latter open at one end and provided with a lateral support flange, said flange having headed retainer-studs and the latter serving to accommodate said key-hole slots, whereby said plate is detachably connectible with said flange.

Other objects, features and advantages will become more readily apparent from the following description and the accompanying sheet of illustrative drawings.

In the drawings:

Figure 1 is a perspective view showing a hair trimming or cutting attachment constructed in accordance with the principles of the present invention and illustrating the manner in which it is fitted for use on an electric razor;

Figure 2 is a perspective view of the adapter with the comb means removed;

Figure 3 is a view in section and elevation based on Figure 1 and which shows, in dotted lines, how the comb means may be adjusted to bring the comb closer to the cutter head of the razor;

Figure 4 is an enlarged fragmentary sectional and elevational view taken on the approximate line 4—4 of Figure 1, looking in the direction of the arrows;

Figure 5 is an elevational view of the readily applicable and removable plate or dual comb means by itself; and

Figure 6 is an elevational view showing in full and phantom lines how the attachment is used in cutting the hair by way of an upstroke and combing the hair back down and smoothing it by way of a downstroke.

It is, of course, obvious that the particular make or kind of electric razor is no part of the invention. It has been found, however, that the particular adapter used lends itself admirably well for employment in connection with a Remington electric razor, the same being denoted in the drawings generally by the numeral 8. The usual reciprocating cutter head construction is denoted at 10.

The adapter will vary in construction according to the kind of razor with which it is to be employed. Therefore, an essential part of the over-all attachment is an appropriate adapter and this is generally denoted by the numeral 12. As perhaps best shown in Figure 2, it not only is such that it conformingly fits the razor, it provides a holder for the razor and makes it possible to actually clamp the razor therein so that the two may be used in firm relationship to insure precision results. Specifically, the adapter takes the form of a receptacle-like receiver which is perhaps best referred to as a tray-type receiver and it therefore is characterized by a bottom 14, which is shaped up to fit the razor.

Incidentally, the razor may be placed in from either side with the adapter being approximately of a depth equal to one-half the thickness of the razor body. Then, too, the bottom 14 conforms to the coacting surfaces of the razor body. The receiver is open at one end, the top in Fig. 2. It is provided on opposite sides with outstanding and suitably shaped flanges, called side flanges 16, 16 and these are duplicates and also have duplicated clearance notches 18, 18 for the switch button 20 on the margin of the razor. The intervening end flange is denoted at 22. At the open end 24 there is a laterally bent support flange 26. This is provided with studs (see Fig. 4) denoted by the numerals 28, 28, said studs passing through the flange and providing headed retainers 30, 30. Also shown in Fig. 4, the central portion of the flange has a tapered hole 32 therein to accommodate a ball-detent 34 which is yieldably held in the opening or hole 32 by way of a coacting portion 36 at the center of a leaf spring. The spring 38 has appropriate bends to impart the necessary ten-

55

60

65

sion on the ball-detent. The end portions 40, 40 of the springs are secured in place by the studs 28, 28.

The adjustable and detachable comb means is denoted as a unit by the numeral 42. This comprises a substantially rectangular plate which as shown in Fig. 5 has a central lengthwise bend 44 which transforms the plate into substantially flat, rectangular half-portions 46 and 48. These half-portions are provided with teeth 50 forming one comb on one side of the plate and additional teeth 52 providing the comb on the other side of the plate. It is also evident from Fig. 5 that the half-portion 48 is provided with longitudinally spaced key-hole shaped slots 54 which are located to accommodate the retainer heads 30 in the manner illustrated in Fig. 4. Opposite side surfaces of this half-portion 48 are provided with small depressions 56 which constitute selectively usable keeper seats for the ball-detent 34 in the manner also illustrated in Fig. 4. The spring thrust ball-detent serves to make sure that the dual comb plate 42 is effectively maintained in position. It is easy to actually snap the plate on and off in a rather obvious manner. That is to say, the larger ends of the key-hole slots are placed over the heads 30 and then the plate is slid endwise bringing the heads into the narrow ends of the slot and holding the plate in position. Sliding of the plate accidentally in an opposite releasing direction is resisted by the ball-detent 34 engaging in the cooperating keeper seat 56. It is also to be noted that the respective combs 50 and 52 are at slight divergent angles and therefore converging toward the bend 44. The purpose of this slight slanting is to permit the plate to be readily applied and removed and the comb 50 turned over or reversed and in this manner is adjusted so that the teeth are farther away from the cutter head 10, as shown in Fig. 3 in full lines, or closer to the cutter head, as shown in dotted lines.

It is also within the purview of the invention to either increase or decrease the angularity of the respective combs so that it is possible to get several spacing adjustments between the cutter head and comb which is then in use. This means that the comb plate 42 may be described as adjustable in the sense that it is reversible simply by taking it off and putting it back on with the desired comb in place either close to or far from the cutter head.

In practice, the razor is seated in the receptacle portion of the tray-like adapter so that the adapter virtually becomes a part of the razor and the two may be grasped and used in a solid properly associated relation as brought out in the drawing particularly in Fig. 6. In full lines in Fig. 6 one sees how the device is held and moved on an upstroke in a vertical path to allow the hair ends to be distributively collected between the slots in the teeth 50. The tips of the hair ends come into cutting relation with the cutter head and thus are clipped off in an obvious manner. The upstroke is the hair cutting stroke and the downstroke is the combing stroke, and at this time, as shown in Fig. 6 in dotted lines the lower comb, here described with the teeth 52 is dragged down as any comb would be to straighten out and smooth the hair for the next cutting stroke. Instead of having to hold a comb in one hand the hair cutter with a single comb in the other hand, both combs are on the one plate making it an unusually handy and reliable construction to attain the desired ends to the utmost in satisfaction.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. For use on and in conjunction with an electric razor; a hair cutting attachment comprising a readily applicable and removable adapter which conforms in shape and size to and constitutes a receiver and firm encompassing holder for said electric razor whereby the adapter and razor may be simultaneously gripped in one hand and pressed into direct contact with each other and operated as a handily maneuverable and controllable entity, detachable means including at least one toothed comb which is reversible and assumes fixed operative relation to the existing or stock cutter means of the usual cutter head of the razor, and additional means for fixing and positively retaining said first named means on said adapter.

2. The structure defined in claim 1, and wherein said first named means embodies two combs, one which serves on an "up" stroke of the razor in a vertical path of movement to collect the hair-ends for cutting, and the other which serves to straighten and comb the hair back to its desired place during the "down" stroke of the razor.

3. The structure defined in claim 1, and wherein said additional means embodies a lateral support flange on which said first named means is detachably mounted.

4. The structure defined in claim 1, and wherein said adapter comprises a tray-like receiver for conformably fitting on and retention of the razor.

5. The structure defined in claim 4, and wherein said receiver embodies a bottom, side flanges and one end flange joining said side flanges, leaving the receiver open at the other end to expose the cutter head of the razor for active cooperation with said comb.

6. The structure defined in claim 5, and wherein said receiver is approximately of a depth which is one-half the thickness of the razor body, the side flanges having clearance notches therein.

7. For use on and in conjunction with an electric razor; a hair cutting attachment comprising an adapter which conformably fits itself to and is handily retained on the body of the razor, a plate having selectively usable toothed combs, and means for detachably and adjustably mounting said plate on said adapter.

8. The structure defined in claim 7, and wherein said means comprises a lateral support flange integral with the adapter, and headed attaching and retaining studs carried by said flange, said plate having key-hole slots releasably connectible with the heads on said studs.

9. As a new article of manufacture, a substantially rectangular plate having a lengthwise central bend defining complementary flat half-portions, the respective outer longitudinal edges thereof being toothed and providing progressively and selectively usable combs, said half-portions being at slight divergent relation in respect to said bend, one of said half-portions having key-hole slots therein.

10. The structure defined in claim 9, and the combination therewith of a tray-like razor receiver and holder, the latter being open at one end and provided with a lateral support flange, said flange having headed retainer-studs and the latter serving to accommodate said key-hole slots, whereby said plate is detachably connectible with said flange.

11. The structure defined in claim 10, and wherein said support flange has a hole therein, a spring biased ball-detent mounted in said hole and supported by way of said support flange, said plate having a keeper seat for said ball-detent.

12. An attachment for holding an electric razor and utilizing the cutter head thereof for purposes of cutting one's hair comprising a concave pan-like receptacle into which the razor is placed and which is open at one end so as to expose the cutter head of the razor, means carried by said receptacle and in alignment with and co-operable with the open end and serving to guide the

ends of the hair to the cutter blades of the cutter head and also serving to regulate the length of the hair which is allowed to remain intact on the user's head.

13. The structure defined in claim 12 wherein said means is characterized by a comb.

14. For use on and in association with an electric razor; a hair cutting attachment comprising a readily applicable and removable adapter which conforms in shape and size to and constitutes a receiver and firm encompassing holder for said electric razor whereby the adapter and razor may be simultaneously gripped in one hand and pressed firmly together and into direct contact with each other and operated and maneuvered as an entity, a plate, means detachably securing said plate on

5 a complemental edge portion of said adapter, said plate having at least one toothed comb, the teeth of said comb being oblique angled in respect to the general plane of the bottom of said adapter whereby upon detaching, reversing and again attaching said plate the said adapter, the distance between the stated teeth and cooperating cutter head of the razor may be varied in a manner to thus meet varying cutting requirements.
